UNITED STATES PATENT OFFICE

BENJAMIN KAPLAN AND LEO ROSENBERG, OF NEW YORK, N. Y.

COAT LINING

Application filed December 16, 1929. Serial No. 414,335.

This invention relates to new and useful improvements in a coat lining.

The invention has for an object the provision of a device of the class mentioned which is of simple durable construction, dependable in use and efficient in action, and which can be manufactured and sold at a reasonable cost.

The invention proposes in combination with a coat or other garment, a lining secured 10 in place along the sides and top so as to be free along its bottom edge, and weights attached along said bottom edge to hold the lining straight while the garment is being worn. The invention also proposes a means 15 for adjusting the mass of said weights and their location.

Coat linings are subjected to greater wearing stresses than the exterior material of the coat. One reason for this is the continual 20 rubbing of the lining against clothes worn beneath the garment. When the lining is attached along all sides bulges occur due to different shrinkage of the material, or other reasons. The raised portions of these bulges 25 particularly rub against the clothes worn beneath the garment and suffer excess wear. According to the instant arrangement, no such bulges can occur in that the lining is free on the bottom and merely maintained 30 straight by weights attached thereon. The elimination of bulged portions of the lining materially adds to its life. The adjustability of the mass of the weight and their location provide for the proper hanging of the lining.

For further comprehension of the invention, and of the objects and advantages thereof, reference will be had to the following description and accompanying drawings, and 40 to the appended claims in which the various novel features of the invention are more particularly set forth.

In the accompanying drawing forming a material part of this disclosure:—

45 Fig. 1 is an elevational view of a coat provided with a lining constructed according to this invention.

Fig. 2 is an enlarged vertical sectional view taken on the line 2—2 of Fig. 1.

50 Fig. 3 is a fragmentary enlarged eleva-

tional view of the inner side of the coat immediately adjacent the opening thereof.

Fig. 4 is a vertical sectional detailed view taken on the line 4—4 of Fig. 3.

Fig. 5 is a view similar to Fig. 3, but illustrating another embodiment of the invention.

Fig. 6 is an enlarged vertical sectional view taken on the line 6—6 of Fig. 5.

The reference numeral 10 indicates generally a coat or other similar garment, 11 a lining secured in place within said coat and along its sides and top so as to be free along its bottom edge 12, and a weight 13 attached along said bottom edge to hold the lining straight while the garment is being worn. The coat 10 as illustrated is for ladies' wear and the dominant parts are the outer material 14 and the said lining 11. The lining 11 terminates a small distance from the bottom of the outer material 14, and the weight 13 is attached to the bottom of the lining and extends substantially to the bottom of the outer material. The weight 13 consists of a strip of heavy flexible material which preferably includes metal threads providing sufficient weight.

As shown, the coat 10 is provided at the opening with a binding strip 15, and the strip of heavy flexible material 13 is inserted between the binding strip and the outer material of the coat and then securely sewn in place. It should be noticed that the flexible material 13 is free along its full length and is only secured down at the ends to the material of the coat and along the top is attached to the bottom of the lining.

In Figs. 5 and 6, a modified form of the invention has been disclosed in which a means for adjusting the mass of the weights and their location is shown in detail. This means consists of short length wires 16 inserted in horizontal passages 17 formed by horizontal stitches 18 in a double piece of heavy flexible material 13 formed with a plurality of spaced transverse cuts 19 extended in from the bottom. The cuts 19 do not reach the top of the material so that at the top it is of one piece. A rubber friction strip 20 is secured within each of the portions of the material 13' between the said transverse cuts and serves to

frictionally hold the wires 16 in place. Stitches 21 serve to attach the flexible material 13' upon the bottom of the lining 11.

Each of the passages 17 may be provided with a piece of wire 16 which weighs down the lining. If a particular wearer deems the weights too heavy or if the lining does not hang properly, it is merely necessary to force some of the short pieces of wire 16 out from the recesses. In this manner, any desired weights may be accomplished and any location thereof. The rubber frictioning strips 20 are depended upon to hold the wires in engaged positions and to permit easy removing.

When the coat is worn, the weighted bottom of the lining serves to properly hold it. This arrangement has all the advantages of the lining being sewed down firmly, but in addition has the advantage that bulging of the lining is not likely to occur which would be apt to cause excessive wear on certain portions thereof. Further, the open bottom of the lining is a more sanitary construction in that air may circulate between the lining and the front material of the coat providing ventilation.

While we have shown and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:—

1. In combination with a coat or other garment, a lining secured in place along the sides and top so as to be free along its bottom edge, and weights attached along said bottom edge to hold the lining straight while the garment is being worn.

2. In combination with a coat or other garment, a lining secured in place along the sides and top so as to be free along its bottom edge, and weights attached along said bottom edge to hold the lining straight while the garment is being worn, said lining terminating at its bottom edge a short distance from the bottom of the coat and said weights being attached on their tops to the bottom of the lining and terminate at the bottoms substantially at the bottom of the coat.

3. In combination with a coat or other garment, a lining secured in place along the sides and top so as to be free along its bottom edge, and weights attached along said bottom edge to hold the lining straight while the garment is being worn, and consisting of a strip of heavy flexible material.

4. In combination with a coat or other garment, a lining secured in place along the sides and top so as to be free along its bottom edge, and weights attached along said bottom edge

to hold the lining straight while the garment is being worn, and consisting of a strip of heavy flexible material, secured at the ends to the material of the coat.

5. In combination with a coat or other garment, a lining secured in place along the sides and top so as to be free along its bottom edge, weights attached along said bottom edge to hold the lining straight while the garment is being worn, and means for adjusting the mass of said weights and their location. 70 75

6. In combination with a coat or other garment, a lining secured in place along the sides and top so as to be free along its bottom edge, weights attached along said bottom edge to hold the lining straight while the garment is being worn, and means for adjusting the mass of said weights and their location, said means consisting of short length wires inserted in horizontal passages formed by horizontal 80 85 stitches in a double piece of heavy flexible material formed with spaced transverse cuts extended in from the bottom and terminating below the top, and rubber friction strips within said passages for frictionally holding 90 the wires in place.

In testimony whereof we have affixed our signatures.

BENJAMIN KAPLAN.
LEO ROSENBERG.
